UNITED STATES PATENT OFFICE.

GEORGE H. WILKINS, OF GREENFIELD, MASSACHUSETTS.

COMBINED SHIPPING-CASE AND DISPLAY-RACK.

1,352,490.

Specification of Letters Patent. Patented Sept. 14, 1920.

Application filed December 29, 1919. Serial No. 348,154.

To all whom it may concern:

Be it known that I, GEORGE H. WILKINS, citizen of the United States of America, residing at Greenfield, county of Franklin, 5 and Commonwealth of Massachusetts, have invented certain new and useful Improvements in Combined Shipping-Cases and Display-Racks, of which the following is a specification.

10 This invention relates to improvements in a combined shipping case and display rack for the purpose of holding mechanics' tools, as screw drivers, drills, files, nail sets, etc., or other like articles of various kinds while 15 being shipped from the factory or manufacturing plant to the jobber or retail dealer, and, combining therewith a structure for displaying these tools or articles after they have been received by the jobber or retail 20 dealer.

An object of the present invention is to provide a box-like structure for shipping and displaying purposes so that the goods may be displayed in the same case in which 25 they are shipped or received and which may be readily changed to exhibit the goods, as mechanics' tools or other wares, to the purchasing public. The invention, broadly considered, comprises a case made up of three 30 members, the base or box member, an intermediate and removable insert or extension member which is designed to be placed within the base member for providing a box or case of the requisite height. This extension member is, as stated, designed to be removed from the base member and discarded 35 when the goods are received, and the cap or cover portion of the box is used for forming a support for holding the tools in an upright 40 position. The cover of the case is provided with a plurality of openings of suitable size for the purpose of holding the tools contained in the case to be exhibited or displayed in vertical positions by placing one 45 of them in each of the openings. The tools so displayed may rest on the bottom part of the base piece, or be supported on the cover, as shown.

For the purpose of properly spacing the 50 cover from the base piece when the case is used to display the goods, posts or uprights are employed which are removably attached to the corners of the base and cover members. These uprights are to be used after 55 the extension member has been removed from the base member. These corner pieces

are preferably formed of thin metal and suitably cut or stamped for receiving the corner portions of the base and cover part of the shipping case.

60 Referring to the drawings:

Figure 1 is a perspective view of the base, extension and cover members separated from each other.

Fig. 2 shows the removable extension 65 member separated from the base portion.

Fig. 3 shows the base-member after the extension member of the case has been removed, the corner supporting pieces placed on the cover and the base member and tools 70 inserted through the openings in the cover.

Fig. 4 is a perspective view in detail of one of the post-like or cover supporting members, and

Fig. 5 is a perspective view in detail of a 75 modified construction of the post-like or cover supporting piece which is attached at the corners of the base and cover.

Referring to the drawings in detail: 1 designates the base-portion or member of 80 the shipping and display case which is preferably composed of strips of thin wood suitably secured together at the corners as by dove-tailing indicated at 2. 3 indicates an extension member of any desired height 85 which is placed inside of the base portion 1 as indicated in Fig. 1. This piece is preferably made of some flexible material as straw board or card board. 4 designates the cover portion of the shipping and display 90 case having its corners secured together by dove tailing indicated at 5. The top portion of the cover is formed with a plurality of vertical openings or holes 6 to receive the tools. 7 designates one of the cover supporting 95 corner posts, preferably formed of thin metal as sheet steel and having two web or flange portions 8 and 9 bent at right angles to each other, as shown. Each of these webs is formed at its opposite ends with struck-up 100 or bent away portions for forming the thin flexible tongues 10 and 11 and providing shoulders 10' and 11' to engage the upper and lower edges respectively of the base and cover. These extension members or corner 105 pieces are made any suitable length, depending upon the purpose for which they are to be used in displaying different articles as bits, drills, screw drivers, files, nail sets and rivet punches, or other mechanics' 110 tools. This display feature of the rack or case is formed as follows: The extension

member 3 is removed from the shipping case in which the tools are packed and shipped to the dealer. The cover supporting corner pieces 7 are then placed on the base piece 1 and the cover portion 4, as shown, by placing the thin integral tongue members 19 and 11 on the inside portions at the corner parts of the base and cover and those parts of the post-like members 7 indicated at 12 and 13 are placed on the outer surfaces of the corner portions of the base and cover respectively.

The tools that are to be exhibited for sale by placing the display rack shown in Fig. 3 on a counter or show case are then inserted in the openings 6, it being understood that the same tools that are shipped to the dealer in the assembled casing shown in Fig. 1 are displayed when the device is used for a display rack, as for example, the screw driver 14 for use in a bit brace, the drill 15, file 16, rivet punch 16', and screw driver 16², if these articles are the ones forwarded to the dealer in the shipping case.

It will be seen from this construction that the improvement combines the double purpose of a shipping case and display rack for mechanics' tools or the like and one that can be constructed at small cost and readily assembled for packing the goods and set up for display purposes. It is also understood that the cover supporting posts or corner pieces 7 are inclosed in the shipping case with the goods so that the dealer has a complete display rack with every shipment.

Fig. 5 indicates a slight modification in which the cover supporting post members 7 are formed with integral struck-up tongue portions 17 from the web portions 8 and 9. These are used in the same manner as already described in connection with Fig. 4.

It should be understood that the length of the cover supporting posts is such that the space between the cover and base-piece is such that the tools will project a suitable distance above the cover for display purposes, as shown in Fig. 3.

It should be observed that the openings

in the cover 4 permit the various kinds of tools to be readily withdrawn from the display rack. It should also be observed that the tools do not necessarily rest upon the bottom or base-piece, but may be supported on the cover as shown, where the screw 55 driver 16² does not rest upon the bottom, but is supported in a pendant manner by the cover; the shank portion extending downward through the opening and the lower edge of the ferrule resting on the 60 cover.

It should be observed that the tools are clearly displayed at their upper and lower ends and that some of them, as the screw driver, are suspended from the cover and 65 do not rest upon the bottom of the box.

What I claim is:

1. A box-like display rack for tools, in combination, comprising a base member, a cover formed with openings therein, means for spacing said members from each other comprising members adapted to be placed on and removed from the base member whereby the articles to be displayed may be inserted in the openings of the cover portion and projecting both above and below the cover for displaying the upper and lower ends of the articles.

2. A combined shipping and display receptacle adapted to receive articles for shipping as mechanics' tools, and including a cover and base-piece, the cover having a plurality of openings in its upper portion to receive the tools, post-like members for supporting the cover in spaced relation above the base-piece when used as a display receptacle, said members comprising angular shaped pieces having offset tongue members at their ends and formed with shouldered portions to engage the upper and lower edges of the base-piece and cover respectively and portions oppositely located to the tongue members and of a length equal to said tongue to engage the inner and outer surfaces of the base-piece and cover respectively and of a length equal to the heights of the base-piece and cover.

GEORGE H. WILKINS.
